W. DIEHL

Des. 143,959

PIN OR SIMILAR ARTICLE

Filed Oct. 6, 1945

FIG. 1

FIG. 2.

INVENTOR

WILLIAM DIEHL

BY

Edwin Leisner

ATTORNEY

UNITED STATES PATENT OFFICE

143,959

DESIGN FOR A PIN OR SIMILAR ARTICLE

William Diehl, Summit, N. J., assignor to Jacques Kreisler Manufacturing Corporation, North Bergen, N. J.

Application October 6, 1945, Serial No. 122,593

Term of patent 7 years

(Cl. D45—19)

To all whom it may concern:

Be it known that I, William Diehl, a citizen of the United States of America, residing at 22 Division Avenue, Summit, New Jersey, have invented a new, original, and ornamental Design for a Pin or Similar Article, of which the following is a specification, reference being had to the accompanying drawing, forming a part thereof.

Fig. 1 is a front elevational view of a pin showing my new design, and
Fig. 2 is an edge view thereof.

I claim:

The ornamental design for a pin or similar article, as shown.

WILLIAM DIEHL.
